UNITED STATES PATENT OFFICE

2,586,330

LIGHT BEAM GUN

Earle G. Henry, Wilmette, and Leo L. Galinski,
Chicago, Ill., assignors to Raymond T. Moloney,
Chicago, Ill.

Application November 18, 1946, Serial No. 710,464

11 Claims. (Cl. 273—101.1)

1

This invention pertains to photoelectric marksmanship apparatus of a type particularly, but not exclusively, adapted to utilization in coin-controlled amusement games, and the like.

An important object is the provision of a moving photoelectric target and novel mechanism for imparting a scrambled, irregular, meandering motion thereto, for the purpose of rendering more difficult and interesting the exercise of skill in training the aiming piece or gun thereupon.

Another object is the provision of a gun or aiming piece which is capable of adjustment of aim in both horizontal and vertical planes, that is to say in bearing and range, azimuth and zenith arcs.

Another object is the provision of fire control or trigger means structurally and functionally cooperative with one of the aim adjustment controls.

A further object is the provision of novel light-shutter and emission means forming part of the gun assembly.

Still another object is the provision of a time-delay circuit for the light shutter to afford rapid-fire action by use of relay means.

Additional objects are the provision of a gun unit which includes as a part thereof, the light source, the shutter means, the azimuth and zenith adjustment means, the fire control means, and mechanism for rendering the zenith and azimuth adjustments non-uniform, the latter as a means of further taxing the skill of the marksman.

Additional objects and aspects of novelty will appear as the following description proceeds in view of the annexed drawings, in which:

Fig. 1 is a horizontal cross section through the game cabinet, showing the gun unit and target-actuating mechanism in plan;

Fig. 2 is a vertical cross section through the game cabinet, showing the gun unit, the target-actuating mechanism and the target proper in elevation;

Fig. 3 is a transverse vertical cross section through the game cabinet showing the target portion in elevation and parts of the target-actuating mechanism in elevation and in section;

Fig. 4 is a rear elevational view of the gun unit, looking in the direction of lines 4—4 of Fig. 1;

Fig. 5 is a top plan view of the gun unit;

Fig. 6 is a vertical section through the gun unit along lines 6—6 of Fig. 5;

Fig. 7 is a vertical sectional detail through the azimuth of horizontal aim adjustment means,

2

looking in the direction of lines 7—7 of Fig. 5; Fig. 8 is a schematic circuit diagram.

By way of introductory description, attention is called to Fig. 8, wherein there is disclosed an 5 aimable gun 10, which may be trained upon a photoelectric target 11 by manipulation of azimuth adjustment wheel 12 and zenith adjustment wheel 13.

Target 11 is moved both horizontally and vertically by a driving mechanism indicated generally 10 at 14 and including a motor 15, it being understood that certain structural details are omitted in the schematic showing of this Fig. 8, to be particularly described hereinafter.

15 To operate the marksmanship apparatus of Fig. 8, a coin is utilized in conventional manner to close a known type of coin and time switch 16, thus connecting power from source 17 to leads 18 so that motor 15 will run for a desired period 20 of time, and also energizing the amplifier unit 19, although it is frequently desirable that the latter unit be continuously energized in locations where the periods of idleness of the game are not too long, thereby eliminating the brief warm-up delay necessary for the usual thermionic amplifier tubes.

With the coin switch closed as aforesaid, the target 11 will be in continuous, complex motion, and when the marksman is satisfied with the aim 30 adjustment of controls 12 and 13, he may initiate a rapid-fire emission of "light bullets" by depressing the azimuth wheel 12, thereby closing contacts 20 to energize the winding 21 of the fire control relay via conductors 22.

35 As a result of energization of the fire control relay, contacts 23 of the latter close, thereby connecting power from the D. C. source conductors 24 (preferably taken from the D. C. power unit of the photoelectric amplifier), through normally closed contacts 26 of the timing relay 27, to the winding of the shutter relay 25, so that the latter pulls up to close its contacts 28—28', thus connecting power from said D. C. source, via conductors 29 to winding 30 of the shutter magnet, and also to the winding (not shown) of the shot counter 31.

As a result of energization of the shutter coil, the latter attracts the spring normalized shutter armature 32, permitting passage of light from 50 lamp 33 to mirror 34 in the gun 10, said mirror being angled to direct the light through the gun barrel onto the photoelectric target 11 for a brief interval.

The firing interval is determined by timing relay means 27, the winding of which is connected

with D. C. voltage as soon as shutter relay contacts 28-28' close, as aforesaid, and so long as the normally closed contacts 26 remain closed.

However, timing relay winding 27 does not at once become fully energized to attract its armature and thereby open contacts 26 until a condenser 35, shunted across the winding 27 becomes fully charged, the time delay afforded by the combination of winding 27 and condenser 35 being a function of the resistance of said winding and the capacity of said condenser. In one satisfactory arrangement, a suitable delay is effected by use of a D. C. voltage of 15 volts applied to a winding resistance of 150 ohms, shunted by a capacity of 100 Mfd.

As soon as winding 27 is fully energized to attract its armature and open contacts 26, shutter relay winding 25 is disconnected from power, and its contacts 28-28' open, thus disconnecting the timing relay 27 from power, so that the timing relay winding 27 is likewise disconnected from power and its contacts 26 fall back to closed condition, whereupon shutter relay 25 is again energized and the cycle is repeated, there being enough delay afforded by the winding and shunt condenser combination 27-35 to give the effect of rapid-fire action to the light shutter 32 so long as the marksman holds closed the fire control switch 20.

Each time the light shutter opens and closes under control of the timing means aforesaid, shot register means 31 advances until a predetermined number of permissible shots has been taken and the register opens a known type of limit switch in series with main power leads 22, thereby stopping the motor 15 and rendering the trigger switch ineffective until another coin is deposited. Each hit scored upon the photoelectric target 11 actuates the hit relay 37 through amplifier 19 to step up the score on hit register 38.

Detailed description

In Fig. 2, the relative disposition of the principal structural parts, including the gun 10, target 11, and target-actuating means 14, is shown in relation to a cabinet 40 having a trough-like bed portion 41 and an upright back cabinet section 42, it being pointed out that in these structural views the power pack, amplifier, and control relay means are omitted for clarity.

The photoelectric target structure includes a vertical rod 45 upon which slides a U-shaped housing 46 containing the photo cell 11A shielded by a suitably apertured target face 11B.

Target housing 46 has sufficient weight to tend to slide downwardly on rod 45, but it is normally urged upwardly by a long spring 47 on said rod and bearing against the offset end 48 of a reciprocating arm 49, which offset end slides on the horizontally curved portion of said rod, the end of said portion being fixed as at 50 in the end of a horizontal sweep arm 51.

Sweep arm 51 carries affixed thereto the motor unit 15, which is of a type having a built-in speed reduction unit driving a vertical spindle 52 journaled in said arm and rotating an irregular scrambling cam 53, seen better in Fig. 1, in view of which the following parts are now described.

At its left-hand end, Fig. 1, the sweep arm 51 is pivotally anchored on a vertical rod 54 (see Fig. 4), so that the opposite or right-hand portion of said sweep arm describes an arc in oscillatory or back and forth motion imparted thereto by means including a crank arm 55 pivotally connected to a radius arm 56 which is in turn

pivotally anchored as at 57, the crank arm 55 rotating with spindle 58, which in turn is driven by pulley 59, fast thereon, through belt drive 60 with the motor spindle 52 (see Fig. 2).

Near its outer or right-hand end, the sweep arm is provided with a cross arm 60 (Fig. 1) on one end of which is carried a roller 61 (see also Fig. 2) which rides on a metal plate 62 extending transversely of the cabinet trough on support 63 (Fig. 2).

On the opposite end of said cross arm 60 is a stabilizing means including a friction drive wheel 65 journaled in bracket 66 and having rotatable therewith a large gear 67 (see Fig. 3) which in turn drives a pinion 68 fast with a flywheel 69; thus, as the sweep arm oscillates back and forth, the flywheel 69 is rapidly rotated by its friction drive and resists jerky alternations in movement of sweep which otherwise appear owing to play in driving components of production embodiments of the game.

The foregoing oscillation of the sweep arm accounts for one component of motion of the target assembly, since the latter is carried by said sweep arm through connection of rod 45 at its lower end with the arm as at 50. The other component of the complex motion of the target is effected through reciprocation of arm 49 (Fig. 2), which exerts compression and relaxation efforts at offset 48 on spring 47, thus elevating and lowering the target housing 46.

An irregular or scrambled motion is imparted to the reciprocating arm 49 through the agency of an oscillatory drive arm 70 (Fig. 1) pivotally connected thereto as at 71 and having a pivotally anchored end 72 on an extension 73 from the sweep arm, there being a cam roller 74 between the said pivoted ends of arm 70 bearing against the irregularly developed edge portions 53A, 53B, 53C of the scrambling cam 53, which is slowly rotated through the speed reduction means of motor 15, it being observed that spring 47 serves also to press said cam roller into operative engagement with the scrambling cam by its action against the offset end 48 of arm 49.

Thus the irregular cam drive imparts a non-uniform motion vertically to the target unit, and owing to some compressibility permitted in spring means 47, there is some additional irregularity in the up and down movement of the target unit, with the result that it is very difficult to predict the position of the target from time to time.

The foregoing target drive means and target structure is regarded as one of the units of the game and is considered to be one of the important inventive elements of the disclosure.

Another important inventive aspect of the disclosure is the gun unit, now described in view of Fig. 4, wherein it will appear that the heretofore described gun 10 includes a hooded breech portion 10A with a dependent (Fig. 6) bracket portion 10B, as well as a base plate 10C pivotally carried on the spindle 54, which in turn is journaled in vertically spaced bracket members 75.

As in Fig. 6, dotted lines, the gun is rockably mounted (for vertical or elevational adjustment) on screw pins 76 engaged in a trunnion bracket 77 through the base of which passes the head of the spindle 54.

As in Fig. 6, vertical motions of the gun are effected by a vertical pin 77X having a headed upper end 78 on the inner side of a slot in the bottom of the gun barrel, said pin sliding in a sleeve 79 on the base plate and having at its lower end a collar 80 which is engaged by down-

ward movement of the edge portion 81 of a yoke bracket 82 (Fig. 4) the opposite arms of which are slideable up and down on spindle 54 with the uppermost arm thereof normally urged upwardly by spring 83.

The weight of the dependent breech bracket portion 10B of the gun normally elevates the muzzle portion thereof; however, downward movement of said yoke bracket will cause the edge portion 81 thereof to press down upon the collar 80, pulling pin head 78 down, with a consequent lowering of the muzzle.

Up and down movement of the yoke bracket is effected by rotation of a cam 84, Figs. 4 and 6, fast on the spindle of control wheel 13, said cam bearing down on a roller 85 fast on the yoke bracket responsive to turning of said wheel in one direction, whilst turning of said wheel in the opposite direction permits spring 83 to raise the yoke with a consequent upward movement of the muzzle under counterweighing of the heavy tail bracket of the gun.

The azimuth or horizontal adjustment of the gun is effected by turning of hand wheel 12, which has, Figs. 4 and 5, a cam 87 fast therewith on spindle 88, such that a cam roller 89 at the pivotal connection of lever arms 90 and 91, under urging of spring 92, pivoting arm or lever 90 at 93, positions lever 91 accordingly, with a corresponding pivoting of the gun base plate 10C by connection 94, it being pointed out that the cam 87, as well as the elevation control cam 84, is developed to provide a non-linear (and in this sense irregular) displacement of the cooperating cam roller means, so that the marksman cannot too easily control the adjustment responses without constant attention and concentration in skillfully following the target.

As shown in Fig. 7 particularly, novel fire-control means includes the provision of trigger switch contacts 20 positioned so that the flexible end portions thereof will be engaged by downward movement of a collar 88A on spindle 88 against the upward normalizing effort of spring 95 encircling the spindle; thus, the marksman may press downwardly on control wheel 12 and close the trigger contacts 20 while also turning the wheel to adjust the horizontal aim component.

The novel light emission and control means is carried in the tail bracket 10B of the gun, and includes a lamp 100 (33, Fig. 8) connected in a power circuit, as in Fig. 8, light from which passes upwardly through a spot-forming aperture means 101 and thence upon a reflector or mirror 102 (34, Fig. 8) angled to reflect the light out through the gun barrel.

Normally, emission of light as aforesaid is blocked by the lower end of a shutter armature 32 (Fig. 6) pivoted as at 104 and yieldingly held in blocking position by spring 105. Energization of the shutter coil 30 as heretofore explained in conjunction with the description of Fig. 8, attracts armature member 32 so that light from the lamp 100 will pass onto the reflector. Rapid-fire opening and closing of said shutter armature is effected by the circuit means described in Fig. 8, under control of fire-control contacts 20 and the time-delay relay means.

Amplifier means for the photoelectric target are not described in detail since the same are well-known in the art and do not per se constitute part of the invention; and for the same reason, hit and shot counter or register means are not shown excepting schematically. Register

means suitable for use as elements 31 and 38 of Fig. 8 are shown in U. S. Patent No. 2,281,262 to Breitenstein, this type of register utilizing a ratchet disc stepped around electromagnetically and carrying numerals optically illuminated or projected by a lamp. In Fig. 3, two windows or sight-openings 109, 110, are shown in the upright section of the cabinet, behind each of which is a corresponding score or hit register dial of the class mentioned, the arrangement of one number bearing dial 111 and corresponding lamp and lense means 112, 113 being shown schematically in Fig. 2, and as in the latter figure, the photo-cell 114 is preferably connected to the amplifier (not seen) by flexible leads 114.

In connection with the circuit means of Fig. 8, and particularly the time-delay, rapid-fire relay means thereof, it is pointed out that condenser and relay elements have been used heretofore to afford various special timing arrangements in conjunction with marksmanship apparatus, as in U. S. Patent No. 2,188,263 to Eisenberg, wherein the predetermined charge on a condenser is utilized to hold up a relay for a length of time determined by setting of a variable resistance, so that the relay will in turn control the length of time a lamp in a light gun is illuminated.

The present control circuit is distinguished from that of said patent and other prior arrangements in that a plurality of mutually controlling relays operate in alternation under control of a time constant determined by a condenser and the resistance of one of said relays, so that a rapid-fire action is effected for a light shutter and a constantly illuminated lamp to give a machine-gun action.

The scope of the invention is not intended to be limited to the precise details of structure and function set forth herein for illustrative purposes, the scope of the invention rather being defined in the annexed claims which are intended to include all modifications and rearrangements of claimed features originating with this disclosure.

We claim:

1. In photoelectric aim apparatus, a rapid-fire light gun mounted for bi-manual aim adjustment in horizontal and vertical planes of movement, a manual control, including non-linear response cam and lever means for adjusting aim in either plane by rotative motion of the corresponding said manual control, one of said controls being movable longitudinally of its rotative axis also, a fire control switch actuated by longitudinal movement as aforesaid of said one control, a light source for said gun, an electrically controlled shutter operable responsive to rapid circuit interruptions to interrupt light from said source outwardly of the gun, and a rapid fire control circuit including said fire control switch and relay means energized thereby and including rapid-fire circuit interruption connections with the winding of said relay means and timed by capacity connected with said winding such that the latter alters the time constant afforded by said capacity in said control circuit.

2. Photoelectric aim means including a gun having a barrel, a breech portion, a pendant bracket from said breech portion, means pivoting the gun for vertical aim at a point between said breech portion and the muzzle, means supporting said gun for horizontal aim, a light source on said bracket, a reflector in said breech receiving light from said source and directing the light through said barrel and muzzle, an electromagnetic impulse-vibrated shutter on said

bracket capable of rapidly interrupting said light from the source, manual controls relatively stationary with respect to the gun for adjusting either component of aim of said gun, a rapid-fire energizing circuit for said shutter, and a fire control switch for said circuit controlled operably by switch means cooperatively related structurally and functionally with a particular one of said manual controls, said particular control having angular motion for aim adjustment and axial motion for operative control of said switch means said angular and axial motions being relative to the same axis.

3. Aim apparatus comprising a support, a gun element mounted on said support for azimuth and zenith movement, a rotatable zenith control and coacting mechanism for displacing the gun element in zenith range, a rotatable azimuth control and coacting mechanism for displacing said gun element in azimuth range said coacting mechanism including non-linear response cams for rendering the corresponding gun element displacement irregular.

4. Apparatus in accordance with claim 3 and further characterized in that at least one of said rotatable controls also has axial freedom of motion, and a fire control element movable by axial displacement of said control.

5. In a photoelectric marksmanship apparatus, an aimable light gun including a light source, a vibratory shutter for said source, an electromagnet adapted to be impelled to vibrate said shutter to simulate rapid-fire action, independently operable zenith and azimuth aim controls for said gun, bracket means mounting all of the foregoing elements in cooperative relationship as a unit, at least one of said controls being mounted to have two modes of movement about and along a single axis which is parallel to the azimuth axis of aim, one of which modes of movement is effective to produce aim adjustment of said gun and another of which is effective for operation of fire-control means for controlling operation of said shutter, and time-delay circuit means cooperable with said electromagnet and controlled by operation of said fire-control means for impulsing the electromagnet to actuate said shutter and effect rapid-fire emissions of light from said gun.

6. In photoelectric marksmanship apparatus of the class described, a light gun and means mounting the same for bi-manual, simultaneous or independent aim adjustments in both zenith and azimuth phases, a light source movable with the gun, an impulse-operated, electromagnetically actuated shutter for said source, at least two selectively operable manual controls for respectively adjusting the azimuth or zenith aim of the gun, a time-delay relay impulse circuit connected with the electromagnetic actuating means for the shutter, a fire-control switch connected in said impulse circuit to start and stop operation of the shutter, one of said manual controls having both rotative and axial freedoms of motion angularly around and also linearly along a common axis and being arranged to effect a certain aim adjustment of the gun in one of its freedoms of motion, and to effect operation of said fire-control switch in the other one of its freedoms of motion, independently of any operation of said control in aim adjustment as aforesaid.

7. In photoelectric marksmanship apparatus, rapid-fire light gun means including a gun aimable simultaneously or independently in horizontal and vertical planes of movement, manuals operable independently or jointly for ad-

justing aim respectively in one of said planes, and a particular one of said manuals being movable oppositely to effect aim adjustment as aforesaid and also being movable in a certain direction different from its movement in aim adjustment for actuation of fire-control means, a fire-control switch actuated by said particular manual in the aforesaid certain direction of movement thereof, a tail bracket pendant from a breech portion of said gun, a light source carried on said bracket, a reflector in said breech portion and directing light from said source through the barrel of the gun, a shutter for interrupting light from said source to said reflector, impulse-actuated, electromagnetic actuating means for the shutter, a direct-current power source for said electromagnetic means, and impulsing means including a pair of mutually controlling relays, one of which has a winding shunted by a capacity to provide a time delay, and circuit connections between said power source and said relays and including said fire-control switch for effecting rapid-fire impulsing of said electromagnetic means responsive to operation of the switch by said particular manual.

8. A gun mounted for at least two modes of aim adjustment, said gun being of a type adapted to have its firing operation controlled by a switch, a first mechanism coacting with said gun and operable to effect adjustment of aim in one of said modes, a manual control for actuating said first mechanism, a second mechanism coacting with said gun and operable to effect adjustment of aim in the second one of said modes, a second manual control having both rotative and linear freedoms of motion respective to a single axis, said second manual control being operable in one of its aforesaid freedoms of motion to operate the second-named adjustment mechanism, and a fire-control switch actuated by said second manual control in its other and remaining freedom of motion.

9. In an aiming device mounted for at least two modes of aim adjustment, said device being of a type having a master control to be actuated by the operator when the aim is adjusted, improvements comprising mechanism cooperable with said aiming device for adjusting the aim of the latter in either of its modes of adjustment separately or together, a first manual control cooperable with said mechanism for operation to effect one of the modes of aim adjustment, a second manual control and means mounting the same for compound or selectively distinct motions in different angular directions rotatively around or back and forth along one and the same axis, means operatively interconnecting said second control with said mechanism to actuate the latter in its second mode of adjustment responsive to operation of the second manual control in one of its angular directions of motion, and a master control actuated by said second manual control in its remaining and other angular direction of motion.

10. Aim apparatus comprising a support, a gun element mounted on said support for azimuth and elevational movement, a rotatable elevation control and coacting mechanism for displacing the gun element in elevational range, a rotatable azimuth control and coacting mechanism for displacing said gun element in azimuth range, said coacting mechanism including non-linear-response cams for rendering the corresponding gun element displacement irregular, together with a tail element offset from the axis of the gun ele-

ment and pendant from one end region thereof and constructed to clear said support in both ranges of motion of the gun element as aforesaid, light means carried by said tail element, and light-directing means situated in said end region of the gun element and optically aligned with said axis of the latter and said light means to direct the passage of light relative to said axis in the gun element and said light means.

11. In a gun mount, a gun including a barrel and means mounting the same for pivotal motion in both vertical and horizontal aiming adjustments, separate manually rotatable controls and coacting mechanism interconnecting the gun and controls for effecting said adjustments jointly or severally, at least one of said controls having an axial freedom of back and forth movement on its axis of rotation in addition to the aforesaid rotatable control movement without affecting the aim adjustment of the aforesaid co-acting mechanism associated therewith, and a fire-control device actuated by movement of said last-mentioned control only in the axial freedom of movement thereof.
